UNITED STATES PATENT OFFICE.

FILIBERTO CONTENTI, OF NEW HAVEN, CONNECTICUT, ASSIGNOR OF ONE-HALF TO
PIETRO TORELLO, OF NEW HAVEN, CONNECTICUT.

GARMENT-FORM.

1,073,960.

Specification of Letters Patent. Patented Sept. 23, 1913.

Application filed September 17, 1912. Serial No. 720,718.

To all whom it may concern:

Be it known that I, FILIBERTO CONTENTI, a subject of Victor Immanuel III, King of Italy, residing at New Haven, in the county 5 of New Haven and State of Connecticut, have invented a certain new and useful Improvement in Garment-Forms, of which the following is a specification, reference being had therein to the accompanying drawings.

10 My invention relates to new and useful improvements in tailors' forms, and has for its object, among other things, to produce a device of this character with means for adjustment of the several elements to accommodate garments for figures of various 15 sizes for forms other than normal.

To these, and other ends, my invention consists in the tailor's form, having certain details of construction and combinations of 20 parts, as will be hereinafter described and more particularly pointed out in the claims.

Referring to the drawings, in which like numerals of reference designate like parts in the several figures: Figure 1 is a side elevation of my improved device; Fig. 2 is a 25 sectional view thereof upon line A—B of Fig. 1; Fig. 3 is a plan view of the upper end of the neck section with some of the parts shown in section upon line I—J of 30 Fig. 2; Fig. 4 is a sectional view upon line G—H of Fig. 2; Fig. 5 is a sectional view upon line E—F of Fig. 2; Fig. 6 is a sectional view upon line C—D of Fig. 2; Fig. 7 is an enlarged view of the hinged mechanism connecting the neck and bust sections; Fig. 8 is a view of the arm bar and a fragmentary portion of the shoulder arm with 35 which it is connected; and Fig. 9 is a side elevation of the slide and arm for adjusting the shoulder.

My improved form is preferably made in three sections, that is, a base section, bust section, and neck section.

The base section is constructed with a 45 spider member 1, which is supported upon a standard 2 and rests upon a fixed collar 3, and to which are hinged the plates 5, 6, 7 and 8. These plates are designed so as to conform in outline to that portion of the 50 human body immediately below the chest, and each is provided with a spring 9, arranged so as to move the upper ends thereof toward each other. A coil spring or any other type of spring may be used equally 55 as well as the one shown.

The bust section is constructed of two members 10 and 11, which combined, are designed to represent the bust of the human figure, and are normally arranged with the edges of the sections abutting against each other in the back, but have an open space 12 between their edges in the front. Upon the lower end of each of these sections is a flange 13, which projects downwardly between the plates 5, 6, 7 and 8, and upon the 60 interior thereof are the inwardly projecting arms 14, which intermesh with each other and are rotatably mounted upon the standard 2, resting upon the fixed collar 15. The members comprising the bust sections are 65 moved, as desired, about the axis of the standard 2 to accommodate chests of various sizes and variations in waist measure are provided for by moving the base section toward and away from the bust section, so 70 that the plates 5, 6, 7, and 8 swing inwardly and outwardly by reason of their contact with the flaring flanges 13. In its new position the base section is secured by the 75 thumb screw 16.

The neck section is constructed of two members 17 and 18, arranged so that normally the members abut at the back, with an open space 19 between them at the front, substantially as shown in Fig. 3. 80 Each of these members is provided with a downwardly projecting wing 20, which is hinged by the pins 21 and 22 to the upwardly projecting wings 23 upon the arms 14—14. Between the wings 20 is the adjusting sleeve 24, which has a finger button 25 at its upper end, and a plug 26 at its lower end, that is provided with a shank 27 that is threaded into a plug 28 fixed in the upper end of the standard 2. The neck section is moved into any of its adjusted positions, the center lines of its extremes being indicated by broken lines in Figs. 1 and 7, by rotation of the sleeve 24, which raises the end of the plug 26 from the inner ends 85 of the pins 21 and 22 by reason of the threaded connection of the shank 27 with the plug 28. When the pressure upon the pins has been released, the neck section is moved to the desired position and there 90 locked by rotation of the sleeve 24 in the reverse direction, the end of plug 26 pressing against the inner ends of the pins 21 and 22. The members 10 and 11 are also locked in 95 their adjusted positions about the axis of 100 the standard 2. The neck section is moved into any of its adjusted positions, the center lines of its extremes being indicated by broken lines in Figs. 1 and 7, by rotation of the sleeve 24, which raises the end of the plug 26 from the inner ends 105 of the pins 21 and 22 by reason of the threaded connection of the shank 27 with the plug 28. When the pressure upon the pins has been released, the neck section is moved to the desired position and there locked by rotation of the sleeve 24 in the reverse direction, the end of plug 26 pressing against the inner ends of the pins 21 and 22. The members 10 and 11 are also locked in 110 their adjusted positions about the axis of

the standard 2 by this same mechanism, as will be apparent from an examination of Fig. 2.

The numeral 29 designates the shoulder pieces, which are adjustably secured at their upper ends to the members 17 and 18 of the neck section through the slotted arms 30, which engage the lugs 31 upon the arms 32 integral with the wings 20. The lower ends 10 of the shoulder pieces 29 are raised and lowered through mechanism which consists of the arms 45, having a knuckle connection 33 with said shoulder plates; slide members 34 connected therewith and guided through 15 openings 35 in the arms 32; and adjusting screws 36 rotatable in the flanges 37 and threaded into the slides 34. Rotation of the screws 36 move the slide members 34 up or down according to the direction of rotation of said screws, and through the arm 45 and connection 33 the outer ends of the said sleeve members will be raised or lowered, the upper ends moving about a pivot 20 through the connection of the slotted arms 25 30 and lugs 31.

Upon both sides of the bust section are the arm members 38, which are supported by the bars 39, pivotally connected with the lugs 40, within said arm members, and projecting through the lugs 41 integral with the arms 45. This bar has a movement through said lug in the direction of its length, and is held against accidental movement 30 through a click device, comprising a pin 42, having an angular head that projects into the teeth upon said bar, and a spring 43 that surrounds the shank of said pin to hold the head in and against the teeth.

Movement of the shoulder members, 40 either up or down, carries with it the arm members, so that they always occupy substantially the same relative position with the outer end of the shoulder members, slots 44 in the bust members 10 and 11 providing means for the uninterrupted vertical movement of the bars 39.

A bust form designed and constructed substantially as shown herein is usable for the purpose of fitting garments having an 50 almost unlimited variation in size and shape, as well as for garments to be worn by persons having a figure that is more or less abnormal.

There are minor changes and alterations 55 that can be made within my invention, aside from those herein suggested, and I would therefore have it understood, that I do not limit myself to the exact construction herein shown and described, but claim all that falls 60 fairly within the spirit and scope of my invention.

Having described my invention, what I

claim as new and desire to secure by Letters Patent, is:

1. In a device of the character described, 65 the combination with a base section, having hinged plates connected therewith; of a bust section, composed of two members, mounted so as to be independently moved about a common axis, and arranged in connection 70 with said base section so that the movement of one of said sections toward and away from the other will move said plates toward and away from each other, depending upon the direction of movement of said 75 member; and a neck section, pivotally connected with said bust section.

2. In a device of the character described, the combination with a base section; of a bust section, composed of two members, 80 mounted so as to be independently moved about a common axis; a neck section, said neck section being composed of members that are rotatable about a common axis; and means for pivotally connecting said neck 85 section to said bust section, said pivotal connection being at substantially a right angle to said last mentioned common axis.

3. In a device of the character described, the combination with a base section; of a 90 bust section, composed of two members, mounted so as to be independently moved about a common axis; a neck section, composed of members that are independently rotatable about a common axis; means for 95 pivotally connecting said neck section to said bust section, at substantially a right angle to said last mentioned common axis; shoulder sections connected with said bust section; and means for adjusting the relative position of said shoulder sections with said bust section, said means being actuated through said neck section.

4. In a device of the character described, the combination with a base section; of a 105 bust section, composed of two members, mounted so as to be movable about a common axis; a neck section, having a hinged connection with said bust section; shoulder members connected with said bust section; 110 members connecting said neck section with said shoulder members; means connected with said neck section for adjusting the position of said members; and arm members mounted upon opposite sides of said bust 115 section, and having an adjustable connection with the shoulder adjusting means.

In witness whereof I affix my signature in presence of two witnesses.

FILIBERTO CONTENTI.
